UNITED STATES PATENT OFFICE.

FRANKLIN A. STEARN, OF PATERSON, NEW JERSEY, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,258,374.

Specification of Letters Patent.

Patented Mar. 5, 1918.

Application filed October 28, 1916. Serial No. 128,307.

To all whom it may concern:

Be it known that I, FRANKLIN A. STEARN, a citizen of the United States, residing at Paterson, in the county of Passaic and State 5 of New Jersey, have invented certain new and useful Improvements in Telephone-Exchange Systems, of which the following is a full, clear, concise, and exact description.

This invention relates to telephone exchange systems, and more particularly to improvements in operators' listening key circuits.

It is the object of this invention to provide means whereby an operator may listen 15 from one cord to another at a high rate of speed.

A feature of the invention is the use of a pair of relays common to all the cords of a position whose interaction controls the 20 disconnection of an operator's head set from a cord circuit and its connection to a second cord.

It is thought that the invention will best be understood from the following detailed description, reference being had to the accompanying drawing. In the drawing the answering end of the connecting operator's cord circuit is diagrammatically shown at the left, while at the right is shown a portion 30 of the listening circuits of a second cord at the same operator's position.

The operation of the system has been described in connection with a sequence switch which controls a district selector, the system 35 in which this sequence switch is used being preferably of the type disclosed in Patent No. 1,168,319. The invention is not restricted to use with such a system, however, since by making changes obvious to one skilled in 40 the art, it may readily be adapted for use with any operator's connecting link circuit.

Assuming that the position is idle and that a call comes in over the line terminating in jack 1, the operator will be informed in the 45 well-known manner by the lighting of the usual line lamp (not shown). She then inserts a plug 2 into jack 1, whereupon a circuit will be completed for relay 3 from ground, winding of relay 3, sleeve contacts 50 of plug 2 and jack 1, to grounded battery, through the winding of the well-known cut-off relay (not shown). At its inner armature relay 3 completes a circuit from grounded battery, armature and back contact 55 of relay 4, conductor 5, inner armature and

front contact of relay 3, contact 102, right-hand armature and back contact of relay 6, right-hand winding of relay 7, to ground. Relay 7 is energized and locks itself to conductor 5 at its inner right-hand armature 60 and front contact. At its outer right-hand armature and front contact parallel circuits are completed for relays 6 and 9. Relay 9 upon energization, connects the calling line to the operator's telephone apparatus. Relay 6 upon energization, locks itself to grounded battery at the outer armature and front contact of relay 3. Relay 7 at its inner 65 left-hand armature completes a locking circuit for itself from grounded battery, armature and back contact of relay 10, winding of relay 4, inner left-hand armature and front contact of relay 7, and left-hand winding of relay 7, to ground. Relay 4 is energized in this circuit and opens the locking 70 circuit through the right-hand winding of relay 7. At its middle left-hand armature, relay 7 completes a circuit from grounded battery, power magnet of sequence switch 100, middle left-hand armature and front 75 contact of relay 7, contact 103 to ground, which moves this sequence switch out of position 1 and into position 2. Further progress of this sequence switch will take place 80 in the well-known manner.

If the operator desires to listen out after learning the number of the wanted line, she depresses listening-out key 16, completing a circuit from grounded battery, contacts of key 16 and winding of relay 10, to ground. Relay 10 attracts its armature and opens the circuit of relay 4, and the locking circuit through the left-hand winding of relay 7. Since the locking circuit through the right-hand winding of relay 7 had been broken 95 at the contacts of relay 4 upon its energization, relay 7 deenergizes and in doing so, opens the circuit of relay 9, thereby disconnecting the operator's telephone set from the talking strands of the cord circuit. The 100 release of the listening-out key 16 deenergizes relay 10.

If now we assume that a call comes in which the operator answers with the cord whose listening circuits are shown at the 105 right of the dotted line, the energization of relay 3', due to the insertion of a plug into the jack of the calling line, will complete a circuit from grounded battery, armature and back contact of relay 4, con- 110

ductors 5, 17, inner armature and front contact of relay 3', right-hand armature and back contact of relay 6', right-hand winding of relay 7', to ground. Relay 7', at its outer 5 right-hand armature, energizes relay 6' and a relay (not shown) corresponding to relay 9 of the first cord, in the manner previously described for relays 6 and 9, and relay 7' at its inner left-hand armature and front 10 contact locks itself to grounded battery over conductor 18, through the winding of relay 4 and the armature and back contact of relay 10. From this point the operation of the circuits is similar to that previously described for the cord shown at the left of the dotted line.

If the operator should plug in on a second cord, such as that shown at the right of the drawing, before depressing listening- 20 key 16, the operation of relay 3' will complete a circuit from grounded battery, outer armature and front contact of relay 3', outer armature and back contact of relay 6', conductors 19, 11, and the winding of 25 relay 10 to ground. Relay 10 is energized and opens the circuit through the winding of relay 4 and the left-hand winding of relay 7, thereby deenergizing relay 7 as before described, and allowing the operator's 30 head set to be connected to the cord whose listening key circuits are shown at the right of the drawing.

If now the operator wishes to listen in again on the cord at the left, she will depress listening key 20 of such cord. A circuit will thereupon be completed from grounded battery, left-hand contacts of key 20, conductor 21, outer left-hand armature and front contact of relay 6, which is locked 35 up as long as relay 3 is energized, conductor 11 and the winding of relay 10 to ground. The operation of relay 10 opens the circuit through the windings of relay 4 and the left-hand winding of relay 7', which relays 40 then deenergize. The deenergization of relay 7' disconnects the operator's telephone apparatus from the cord indicated at the right, and the deenergization of relay 4 completes a circuit from grounded battery, 45 armature and back contact of relay 4, right-hand contacts of listening key 20, conductor 22, right-hand armature and front contact of relay 6, and the winding of relay 7 to ground. Relay 7 is energized as before and 50 the connection to the operator's head set is made as previously described.

It is to be noted that in this arrangement all the relays are positively actuated, no margins being employed.

60 If now the operator, after inserting plug 2 into jack 1, thereby listening in on the cord shown at the left of the dotted line, does not set up a number on her key set, the sequence switch 100 associated with such cord will not leave position 2. If she then

answers another call with the cord shown at the right of the dotted line, her head set will be connected with this second cord and relay 7 will deenergize. The deenergization of relay 7 will complete a circuit from 70 grounded battery, relay 25, outer left-hand armature and back contact of relay 7, contact 104 to ground. Relay 25 is energized and locks up until sequence switch 100 arrives in position 1 over a circuit from 75 grounded battery, contact 105, left-hand armature and front contact of relay 25 to ground, and completes a circuit at its right-hand armature from grounded battery, power magnet of sequence switch 100, right-hand armature and front contact of relay 25 to ground, which returns sequence switch 100 to its normal position. When sequence switch 100 arrives in its normal position, the same conditions exist which caused the operator's head set to be listened in on the cord shown at the left of the drawings; and if it were not for relay 6, she would be again listened in on the cord shown at the left, thereby disconnecting her from the 90 cord shown at the right of the dotted line. This undesirable operation is prevented by the actuated condition of relay 6, which remains locked up as long as plug 2 remains in jack 1, and at its right-hand armature holds open the circuit over which relay 7 was energized when plug 2 was first inserted in jack 1 with sequence switch 100 in position 1.

The operation of returning sequence switch 100 to its normal position in case the operator answers another call without depressing any keys as described, differs somewhat from that disclosed in the above mentioned patent, since in the present invention 105 no listening key sequence switch is employed. Nevertheless the operation is fundamentally the same, since in the system of reference the operator would be listened out of the desired cord if she plugs in with 110 such cord before depressing keys associated with the cord which she had previously used to answer a call.

What is claimed is:

1. In a telephone exchange system, a plurality of subscribers' lines, a plurality of link circuits for interconnecting said lines, an operator's head set, relays, one for each circuit, to control the connection of said head set to said link circuits, energizing circuits for said relays, locking circuits for said relays, means for completing said energizing circuits, and automatic means common to said link circuits for opening any existing locking circuit whenever an energizing 125 circuit is completed.

2. In a telephone exchange system, a plurality of subscribers' lines, a plurality of link circuits for interconnecting said lines, an operator's head set, relays, one for each 130

- link circuit, to control the connection of said head set to said link circuits, energizing circuits for said relays, locking circuits for said relays, means for completing said energizing circuits, and a relay combination common to said link circuits for opening any existing locking circuit whenever an energizing circuit is completed.
3. In a telephone exchange system, a plurality of subscribers' lines, a plurality of link circuits for interconnecting said lines, an operator's head set, relays, one for each link circuit, to control the connection of said head set to said link circuits, energizing circuits for said relays, locking circuits for said relays, a pair of relays common to said link circuits, and means including said relays for opening any existing locking circuit whenever an energizing circuit is completed.
- 20 4. In a telephone exchange system, a plurality of subscribers' lines, a plurality of link circuits for interconnecting said lines, an operator's head set, relays, one for each link circuit, to control the connection of said head set to said link circuits, energizing circuits for said relays, locking circuits for said relays, a relay common to said link circuits arranged to have its winding included in series with said locking circuits, a second relay common to said link circuits, said second common relay controlling at its contacts said locking circuits.
5. In a telephone exchange system, a plurality of subscribers' lines, a plurality of link circuits for interconnecting said lines,
- an operator's head set, relays, one for each link circuit, means for energizing said relays, a relay common to said link circuits, means including said relay to allow only one of said relays to be energized at a time, 40 means for connecting said common relay in series with whichever one of said first mentioned relays has been energized, a second relay common to said link circuits, and means including contacts of said second relay for opening said series connection.
6. In a telephone exchange system, a plurality of subscribers' lines, a plurality of link circuits for interconnecting said lines, an operator's head set, means to connect said head set to a link circuit, a controlling switch associated with each of said link circuits, means to advance said controlling switch to a waiting position, means to connect said head set to a second link circuit, 50 means simultaneously operative to disconnect said head set from said first link circuit, means operative upon such disconnection to restore said controlling switch to its normal position if it is still in waiting position when such disconnection occurs, and means to prevent reconnection of said head set to said first link circuit and disconnection of said head set from said second link circuit when said controlling switch reaches 60 its normal position.

In witness whereof, I hereunto subscribe my name this 27th day of October, A. D. 1916.

FRANKLIN A. STEARN.
